UNITED STATES PATENT OFFICE.

GEORGE ZINT, OF WAPAKONETA, OHIO.

MECHANICAL MOVEMENT.

Application filed October 10, 1927. Serial No. 225,342.

The invention relates to improvements in mechanical movements for sprinklers and aims to improve over the constructions shown by my U. S. Patents 1,146,228, of 5 July 13, 1915 and 1,521,062 of December 30, 1924.

One object of the invention is to provide new and improved driving means for a carrier by means of which the sprinkler head 10 is turned about a vertical axis.

A further object is to provide a construction in which the above-named driving means is encased in a lubricant-containing housing from which water is excluded, thus 15 insuring smooth and easy operation, and preventing danger of corrosion if material be employed which would otherwise be subject to rust and the like.

The above-named carrier supports most 20 parts of its driving means, and a still further object is to construct it in a simple and inexpensive manner, such construction however being efficient and advantageous.

It is preferable that the carriers move first 25 in one direction and then in the other, and to accomplish this, the driving means embodies a reverse gear. This reverse gear includes a sliding clutch whose position is reversed to change the direction of drive, 30 and it is another object of the invention to provide novel and advantageous shifting means for this clutch, overcoming any possibility of said clutch accidentally remaining in a neutral, inactive position.

35 With the foregoing and minor objects in view, the invention resides in the novel subject matter hereinafter described and claimed, the description being made with reference to the accompanying drawing.

40 Fig. 1 is a side elevation of portions of a sprinkler embodying my improvements.

Fig. 2 is a side elevation looking in a different direction, partly in section, as indicated by line 2—2 of Fig. 1.

45 Fig. 3 is a horizontal sectional view substantially on line 3—3 of Fig. 2.

Fig. 4 is a vertical sectional view on line 4—4 of Fig. 2, a number of parts however being in elevation.

50 Fig. 5 is a view similar to Fig. 4, all parts on the line 4—4 of Fig. 2 however, being in vertical section.

Fig. 6 is a view similar to Fig. 4 but showing the sliding clutch shifted to its other 55 position.

Fig. 7 is a vertical sectional view on line 7—7 of Figs. 1 and 5.

Fig. 8 is a vertical section on line 8—8 of Fig. 5.

The form of construction disclosed in the 60 accompanying drawings, has proven advantageous both from a manufacturing standpoint and as to efficient operation, and hence this construction may be considered as preferred. However, even though this construction 65 will be herein specifically described, it is to be understood that within the scope of the invention as claimed, variations may be made.

In the drawings above briefly described, 70 the numeral 9 designates a hollow body supported by a pipe 10 which conducts water to said body. Resting on this body and secured against rotation with respect thereto, 75 is a worm wheel 11, said wheel and body being preferably secured together by a portion of a coupling member 12 which is threaded into the upper end of said body as shown in Fig. 2. The upper end of this coupling member 12 carries a stuffing box 80 13 through which a tubular neck 14 passes rotatably, said neck being secured to an appropriate spray head 15 which preferably embodies two nozzles 16—17, said head being held against accidental upward movement by a rod 18 which is secured to it and passes downwardly through the neck 14 and body 9, said rod being provided with a thrust bearing disposed in the housing 19. The construction associated with this housing 90 is disclosed and protected by my U. S. Patent No. 1,633,879 of June 28, 1927.

Lying upon the worm wheel 11 is a carrier 20 which is pivoted concentrically with said wheel for movement with respect thereto, 95 said carrier embodying a flat horizontal plate-like portion 21 having an opening 22 through which a portion of the coupling member 12 passes to establish the pivotal mounting of said carrier.

An outer edge of the carrier portion 21 is formed with a notch 23, with a downwardly projecting lug 24 at one side of this notch, with a downwardly projecting flange 25 at the opposite side of said notch, and with a second lug 26 projecting horizontally into said notch between said sides. Two vertical arms 27—28 rise from the portion 21 of the carrier 20 at the opposite sides of the notch 23, arm 27 being directly above lug 24 and 105 110

arm 28 directly above flange 25. The upper ends of these arms are formed with horizontally aligned bearing openings 27^a—28^a respectively. Similarly, the lug 24 and the flange 25 are formed with horizontally aligned bearing openings 24^a—25^a respectively. Two additional arms 29—30 rise from the lug 26, these arms being disposed at opposite sides of the axes of the bearing openings 27^a—28^a and being themselves formed with horizontally aligned bearing openings 29^a—30^a whose axis is transverse to and afore said axis of the openings 27^a—28^a. The arm 29, the arms 27—28, the lug 24 15 the flange 25, and the lug 26 are all integral with the plate-like portion 21 of the carrier 20 and this portion is also preferably provided with a downwardly projecting flange 31 at an angle to the flange 25 and connected with the latter and with said lug 24. The arm 30^a however, is preferably separate from the lug 26 to assist in assembly and disassembly, but is rigidly secured to said lug by a screw 32 (Figs. 3 and 8), said arm 25 30 being held against turning upon the screw, by a shoulder 33 which underlies the lug 26 as shown in Fig. 8.

A lower horizontal shaft 34 is rotatably mounted in the lower bearing openings 24^a—25^a; an intermediate horizontal shaft 35 is rotatably mounted in the intermediate bearing openings 27^a—28^a, and an upper, horizontal, rock shaft 36 is mounted in the bearing openings 29^a—30^a and is consequently disposed transversely above the shafts 34—35. Shaft 34 is provided with a worm 37 which meshes with the teeth of the worm wheel 11, and shaft 35 is provided with a worm wheel 38 meshing with a worm 39 on a vertical shaft 40, driven by a water wheel 41. Driving connections are employed between the shafts 35—34 for driving the latter in either direction, even though the former is only driven in one direction by the parts 41—40—39—38. These driving connections will be hereinafter fully described.

Near the periphery of the worm wheel 39, the carrier portion 21 is provided with an upstanding arcuate flange 42 which is integral with said portion. A short vertical tube 43 has its lower end secured against the inner side of this flange, the upper and lower ends of said tube containing ball or other appropriate bearings 44 for the shaft 40. The worm 39 is also disposed in this tube, meshing of this worm with the wheel 38, being permitted by an opening 45 formed in the tube.

The construction just described, provides 60 simple, yet efficient and durable vertical bearing means for the shaft 40.

Two gear trains 46—47 are provided at the inner sides of the arms 27—28 respectively, said trains extending between the shafts 35—34 to drive the latter in either

direction and embodying gears 46^a—47^a, both of which are loose upon the shaft 35. Slidable on and driven by this shaft, is a clutch member 48 which is disposed between the gears 46^a—47^a, said clutch and gears being provided with co-operable clutch teeth 49 which are preferably slightly hook-shaped as shown so that there is no danger of accidental disengagement after they are once engaged. The clutch 48 is formed with a wide peripheral groove 50 which receives clutch-shifting arms 51, said arms being secured to the shaft 36 and projecting downwardly therefrom between the arms 29—30. These arms 51 are of a width considerably less than the width of the groove 50, permitting appreciable movement of said arms in either direction, before effecting movement of the clutch 49. Provision is made for turning the shaft 36 until the arms 51 pass a neutral position at which they start to disengage the teeth 49, and additional provision is made for rapidly turning the shaft 36 to complete the clutch shifting movement of the arms 51, when the latter have been moved slightly past said neutral position. This insures rapid shifting of the clutch 48 from engagement with gear 46^a into engagement with gear 47^a or vice versa, and insures that said clutch shall by no possibility stop at a neutral, idle position.

For turning shaft 36 to dispose the arms 51 slightly past the above-named neutral position, the outer end of said shaft is provided with a downwardly projecting arm 52 which is co-operable with relatively adjustable trips 53 which project from the body 9. It will thus be seen that when worm 37 has traveled sufficiently around the worm gear 11 to turn the sprinkler head 15 in one direction to a predetermined extent, arm 52 will strike one of the trips 53, so that it will effect reversing of the drive between the shafts 35—34, thus correspondingly reversing the worm 37 and causing turning of the sprinkler head 15 in the opposite direction.

At the limit of this turning, arm 52 strikes the other trip 53 and hence the gearing is again reversed. Consequently, it will be seen that the sprinkler head is made to oscillate slowly and that the extent of its oscillatory movement, may be readily controlled by varying the space between the trips 53.

Secured to and projecting downwardly from the inner end of the shaft 36, is an additional arm 54 which is co-operable with a spring arm 55 to effect rapid turning of said shaft 36 in one direction or the other, after it has been moved slightly past a neutral position, under the influence of the arm 52 and one or the other of the trips 53. One end of arm 55 is anchored to the carrier 20 by a screw or the like 56, and said spring is so shaped as to provide it with angularly related end portions 57—58 and a crest 59 be-

tween said end portions. When the arm 54 is in the position shown in Fig. 3 and the shaft 36 is turned by the arm 52 and the co-acting trip 53, it engages the end portion 57 of the spring 55 until it moves slightly, past the crest 59. Then, the resiliency of the spring comes into play and so acts upon the arm 54 as to cause the end portion 58 to move said arm 54 quickly to its reversed position. This rapidly turns the shaft 36 to shift the clutch 48. When shaft 36 is turned in the other direction, as soon as arm 44 passes the crest 59, the end portion 57 of the spring 55 of course effects quick turning of 15 said shaft to produce clutch shifting.

Around the gearing 46-47 and associated parts, I provide a housing 60 to contain grease or other lubricant, insuring free and easy operation of parts and excluding water 20 from them, so that there is no danger of corrosion even if materials be used which would otherwise be subject thereto. Two of the side walls of this housing may well be soldered to the flange 42 and the tube 43 as indicated at 61 and 62, the lower parts of these walls being similarly secured to the upper side of the plate-like portion 21 of the carrier 20. One of these side walls is preferably notched to receive the lug 24 as seen in Figs. 30 2 and 6 and in order to prevent escape of grease through the opening 24^a, this lug is preferably provided with a stuffing box 63. The bottom of the casing is preferably provided with an upturned flange 64 soldered 35 or otherwise secured to the lug 24 and to the flange 31, as seen most clearly in Figs. 7 and 8. One side wall of the housing 60 carries a stuffing box 65 through which the shaft 36 passes, preventing any escape of lubricant. 40 The top 66 of this housing 60 is preferably removable and is provided with an upstanding tube 67 through which the shaft 40 passes, said shaft having a water shed 68 telescoped with said tube. By upwardly shifting 45 the top 66 until its flange 69 clears the body portion of the housing 60, said top may be swung aside, permitting filling of the housing with grease.

Excellent results are obtainable from the 50 construction shown, and as above stated, this construction is therefore preferably followed. However, within the scope of the invention as claimed, variations may of course be made.

55 I claim:—

1. In a mechanical movement, a carrier plate formed with a notch in one edge, a downwardly projecting lug on the plate at one side of said notch, a downwardly projecting flange on said plate at the other side of said notch, a second lug on the plate projecting horizontally into said notch between said sides thereof, parallel arms rising from the plate at said sides of said notch and having horizontally alined bearing openings,

the first named lug and said flange being formed with similar openings, additional parallel arms rising from said second lug at opposite sides of the axis of the first named bearing openings, the upper ends of said additional arms having alined bearing openings whose axis is above and transverse to the aforesaid axis, vertical bearing means on the plate near one of the first named arms; a lower shaft in the bearing openings of said flange and the first named lug, an intermediate shaft in the bearing openings of the first named arms, an upper shaft in the bearing openings of said additional arms, and a vertical shaft in said vertical bearing means; 70 gearing connecting said vertical and intermediate shafts for driving the latter in one direction, two gear trains at the inner sides of said first named arms and extending between the intermediate and lower shafts for 75 driving the latter in reverse directions, a sliding clutch on and driven by said intermediate shaft, and means on said upper shaft for sliding said clutch into engagement with either of said gear trains, said clutch and 80 said clutch-sliding means being disposed between said additional arms.

2. In a mechanical movement, a carrier plate formed with a notch in one edge and having downwardly projecting shaft bearings at opposite sides of said notch, a lug on said plate projecting horizontally into said notch between the sides thereof, parallel arms rising from the plate at said sides of said notch and having horizontally alined bearing openings, additional parallel arms rising from said second lug at opposite sides of the axis of said bearing openings, the upper ends of said additional arms having alined bearing openings whose axis is above 95 and transverse to the aforesaid axis, vertical bearing means on the plate near one of the first named arms, a lower horizontal shaft mounted in said downwardly projecting bearings, an intermediate shaft in the 100 bearing openings of the first named arms, an upper shaft in the bearing openings of said additional arms, and a vertical shaft in said vertical bearing means; gearing connecting said vertical and intermediate shafts for 105 driving the latter in one direction, two gear trains at the inner sides of said first named arms and extending between the intermediate and lower shafts for driving the latter in reverse directions, a sliding clutch on 110 and driven by said intermediate shaft, and means on said upper shaft for sliding said clutch into engagement with either of said gear trains, said clutch and said clutch sliding means being disposed between said additional arms.

In testimony whereof, I have hereunto affixed my signature.
